UNITED STATES PATENT OFFICE.

MIRIAM N. NEUGASS, OF NEW YORK, N. Y.

DESIGN FOR A DOLL.

Application filed February 19, 1929. Serial No. 30,128. Term of patent 14 years.

To all whom it may concern:

Be it known that I, MIRIAM N. NEUGASS, a citizen of the United States, residing at New York city, in the county and State of New York, have invented a new, original, and ornamental Design for a Doll, of which the following is a specification, reference being had to the accompanying drawing, forming part thereof.

design of a doll.

I claim:
The ornamental design for a doll, as shown.

MIRIAM N. NEUGASS.
